UNITED STATES PATENT OFFICE.

MORRIS MEYERSON, OF JACKSONVILLE, FLORIDA.

DESIGN FOR A PUNCH.

54,648.

Specification for Design.

Patented Mar. 9, 1920.

Application filed April 5, 1916. Serial No. 89,221. Term of patent 7 years.

To all whom it may concern:

Be it known that I, MORRIS MEYERSON, a citizen of the United States, residing at Jacksonville, in the county of Duval and State of Florida, have invented a new, original, and ornamental Design for a Punch, of which the following is a specification, reference being had to the accompanying drawing, forming part thereof.

Figure 1 is a front elevation of a punch, showing my new design.

Fig. 2 is a side elevation thereof.

I claim:

The ornamental design for a punch, as shown.

MORRIS MEYERSON.
